DESIGN FOR A TUMBLER

Albert J. Dreitzer, New York, N. Y.

Application February 18, 1935, Serial No. 55,481

Term of patent 3½ years

To all whom it may concern:

Be it known that I, Albert J. Dreitzer, a citizen of the United States, resident of Manhattan, in the county of New York and State of New York, have invented a new, original, and ornamental Design for Tumblers, of which the following is a specification, reference being had to the accompanying drawing, forming part thereof.

The drawing is a perspective view of the tumbler showing my new design.

The dominant feature of the design consists of an arrangement, in relief, of circumferentially disposed vertical leaves.

I claim:

The ornamental design for a tumbler substantially as shown and described.

ALBERT J. DREITZER.
